UNITED STATES PATENT OFFICE.

LOUIS P. DISS, OF ILION, NEW YORK, ASSIGNOR TO REMINGTON TYPEWRITER COMPANY, OF ILION, NEW YORK, A CORPORATION OF NEW YORK.

TYPEWRITING-MACHINE.

1,383,699.

Specification of Letters Patent.

Patented July 5, 1921.

Application filed November 12, 1919. Serial No. 337,434.

To all whom it may concern:

Be it known that I, LOUIS P. DISS, a citizen of the United States, and a resident of Ilion, in the county of Herkimer and State of New York, have invented certain new and useful Improvements in Typewriting-Machines; and I do hereby declare that the following is a full, clear, and exact description thereof, which will enable others skilled 10 in the art to which it appertains to make and use the same, reference being had to the accompanying drawings, and to the reference-numerals marked thereon, which form part of this specification.

15 My present invention relates to type writing machines.

The purpose of my invention is to provide improved means for automatically locking the escapement wheel or mechanism of 20 a type writing machine from operation during the retraction of the carriage and, either separately therefrom or combined therewith, improved means for locking the escapement mechanism from operation after the carriage 25 has completed a pre-determined line.

Further purposes of my invention are to provide simple, efficient and durable arrangements and combinations of parts and elements for accomplishing the general ends 30 desired.

Another object is to provide automatically-operating locking mechanism of either or both of the kinds mentioned that will be entirely out of the way and stationary until 35 the occasion arises for them to become operative.

Figure 1 is a rear elevation of the relevant parts of a type writing machine embodying my invention, the frame being shown in 40 section.

Fig. 2 is a top or plan view of the same as seen from the rear of the machine, but with all but the two operating teeth of the escapement wheel removed.

45 Fig. 3 is a vertical sectional view of the escapement wheel and a left hand side elevation of the dog rocker as seen from Fig. 1.

Referring to the drawings in a more particular description it will be seen that I 50 have illustrated my invention in connection with a modified No. 10 Remington typewriter. The frame includes top plate 10 supported by rear posts 11 and forward

posts 12. Upon the frame is a movably mounted carriage of which there is shown 55 only the hook 13 whereby the carriage is connected to one end of the carriage strap 14, the other end of which is connected to and wound upon the band wheel 15 upon the frame of the typewriter in the usual way so 60 as to yieldingly draw the carriage across the machine during the writing movement of the machine. During retraction of the carriage in the usual way and by the usual methods the carriage strap 14 would have 65 its direction of movement reversed and would be unreeled from the band wheel 15. The machine being viewed from the rear in Figs. 1 and 2, it will be understood that during the feeding or writing movement of 70 the machine the carriage strap 14 will pass from left to right, and during retraction of the carriage the carriage strap will be moving from right to left as the parts are seen in said Figs. 1 and 2.

75 The escapement mechanism resembles in many respects that shown and described in the patent to George A. Seib, No. 1,289,934, dated Dec. 31, 1918. It includes a toothed escapement wheel 16 mounted upon the 80 frame of the typewriting machine and operatively connected to the carriage in the usual or any proper manner so as to allow feeding movement of the carriage to take place step by step and only as the escapement 85 wheel is released through its teeth 17 being successively disengaged from the dog 22 mounted upon the dog rocker 19. Said dog rocker 19 is suitably mounted upon the frame of the machine and operates in the 90 way common to this type of escapement mechanism, so will be only briefly described. The dog rocker is shown as mounted upon a horizontal shaft 21 at right angles to the axis of the horizontal shaft of the escapement wheel 16. Upon the body of the dog rocker there is provided an upwardly extending holding dog 22 rigidly secured to or integral with said dog rocker. The stepping dog 18 is upon the forward side of the dog rocker, or upon the further side as the parts are seen in Fig. 1. Said movable or stepping dog 18 is mounted upon the dog rocker as by means of said dog having a pivot shaft 23 extending through the body 100 of the dog rocker from the forward to the

rear side and there provided with a collar 24 to which the pivot is secured as by pin 25. This collar 24 conveniently forms the means of keeping the pivot 23 in place and 5 also forms the means of connecting said movable dog to its spring 26 which is coiled about the rearward extension 27 formed upon the dog rocker. One end of said spring is secured to the collar 24 while the forward 10 end of said spring is secured to the dog rocker. The tension of said spring is such as to yieldingly force the upper end of said dog 18 to the right as shown in Fig. 1, or against the teeth 17 of the escapement wheel 16. While the machine is in readiness for 15 its forward movement but the escapement mechanism is not being operated the said stepping dog 22 occupies the position indicated in Fig. 1 where its face is in line with the face of the fixed dog 22. A set screw 28 in the upper end of the dog rocker, to the left of the stepping dog 18, has its forward end extended through the dog rocker and serves as a stop to prevent the stepping dog 25 from being forced beyond this position through the tendency of the escapement wheel 16 to move in a clock-wise direction. The escapement mechanism is operated through the downwardly extending lug 29 30 upon the dog rocker 19, being moved rearwardly of the machine or to the right as the parts are shown in Fig. 3 by means of operating link 30 which is connected with the rest of the machine so as to receive a rearward impulse upon depression of any type key or upon depression of any of the spacing keys in the usual manner. A link for this purpose and suitably connected with the remainder of the machine, is shown in the Seib 35 patent hereinbefore referred to. The result of the rearward movement of the lug 29 is to move the upper part of the dog rocker forward so that the stepping dog 18 is moved forwardly of the machine and out of engagement with its tooth 17^a and the fixed dog 40 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 - ment of my invention, my said stop spring does not closely engage the back of the teeth 17 but has its free end spaced a little therefrom thus allowing the escapement wheel to 5 make a backward movement amounting to part of a letter space when the tension upon the escapement wheel is overcome as during retraction of the carriage for a purpose to be hereinafter pointed out.
- 10 To the right of the escapement mechanism as the parts are seen in Figs. 1 and 2 there is provided and located upon the top of the top plate 10 a bracket 33 providing the bearing for a short rock shaft 34, to the rearward end of which or the near end of which, as the parts are viewed in Figs. 1 and 2, there is fixed the locking arm 35. The free end of said locking arm 35 is in line with the space normally left between the tooth 15 17^b upon the escapement wheel and an ear 36 provided upon the dog rocker 19 opposite said tooth 17^b. The arm 35 is adapted to be moved so that its end will enter the space left between said ear 36 and escapement 20 wheel tooth 17^b or may be withdrawn from that position to the position shown in Fig. 1. When said locking arm is moved into the space between said ear 36 and the tooth 17^b it locks or blocks any movement of the escapement mechanism for the reason that the first step of an escapement movement is to have the upper end of said dog rocker move forwardly of the machine as herein above described. It will be seen therefore that as 25 30 35 long as the locking arm 35 is in locking position the escapement mechanism will be locked or rendered inoperative and further forward or feeding movement of the carriage will be prevented.
- 40 It will be understood that the use of the escapement wheel tooth 17^b in this locking mechanism is not essential but is used as simply the most convenient part of the machine fixed against forward movement 45 against which the forward side of the locking arm may be braced when said locking arm is moved into position against the ear 36 upon the dog rocker. The locking arm 35 and its connected parts might be made 50 large enough and stiff enough to perform this work without the arm being braced near its free end. But for quickness and delicacy of operation I prefer to form said locking arm 35 relatively light and brace 55 its free end against some part of the machine which is fixed against forward movement. It will be obvious that the locking arm could be braced by any other adjacent part of the machine suitable for that purpose. It will be understood that the free 60 end of the arm 35 is sufficient in thickness to occupy the space left between the ear 36 upon the dog rocker and the oppositely located tooth 17^b. On the other hand the ear 65 36 is so arranged and spaced from the escapement wheel and its teeth 17 that when the locking arm is not interposed the dog rocker may make its usual motion and its forward end move forward carrying therewith the ear 36 without the said ear engaging any of the teeth upon the escapement wheel.
- 70 The means for moving the locking arm 35 into position during retraction of the carriage and for disengaging said locking arm 75 during the feeding movement of the carriage is a shoe or other suitably shaped member 37 fixed upon the forward end of the rock shaft 34 above and in line with and extending down to the carriage strap 14. 80 The bottom of said friction shoe or member 37 is in the form of a part of a wheel and in constant light frictional engagement with the carriage strap.
- 85 During the feeding movement of the carriage the carriage strap 14 passes toward the right of the machine as the parts are seen in Figs. 1 and 2 and through the frictional engagement of the shoe 37 with said strap the locking arm 35 is moved downward or out of locking engagement with the dog rocker. After the locking arm has thus been moved into inoperative position further movement of the carriage and carriage strap simply results in the strap sliding by 90 the friction shoe 37 and operates to keep said locking arm depressed. As soon as the carriage starts to be retracted the direction of movement of the carriage strap 14 is reversed and said strap moves to the left as 95 the parts are seen in Figs. 1 and 2. The frictional engagement between said strap and the friction shoe 37 at once moves said shoe 37 in the same direction or to the left and thereby elevates the free end of the locking arm 35 into locking engagement 100 with the dog rocker. Further retraction of the carriage causes the carriage strap to slip past the friction shoe 37 and simply exerts sufficient friction to keep the locking arm elevated into locking position.
- 105 The considerable space shown between the tooth 17 of the escapement wheel 16 and the stop spring 32 is to insure a feed movement of the carriage after its retraction is completed, and before it can come to a state of rest for the commencement of a line of print. The said feed movement is a fraction of a letter space whereby the interposing arm 35 is moved out of the path of the ear 36 and 110 whereby the escapement is released. During the retraction of the carriage, the stepping dog 18 is released from the force of the carriage feeding spring, whereby the weaker spring 26 is free to actuate the stepping dog 18 and whereby the escapement wheel 16 is turned back until the tooth 17^b butts 115 against the stop spring 32. Thus the carriage is prevented from reaching its state of rest 120 or printing position until it has made a 125 130

fraction of a letter space movement sufficient to move the interposing arm out of the path of the ear 36.

I will now point out the construction 5 whereby part of the above described means including said interposing arm used for effecting a locking of the escapement mechanism during the return movement of the carriage may with additional parts be used 10 also or only to perform the usual function of a line-lock that is to prevent type reaching the platen after a line of print of predetermined length is completed.

The said improved line-lock consists of 15 means for actuating the interposing arm 35 by the feeding movement of the carriage whereby its movement will be in the opposite direction to its movement effected by the carriage strap 14 during feeding movement 20 of the carriage.

For said purpose there is provided the rock shaft 39 supported as shown by the front and rear posts 12 and 11 respectively of the main frame. On the rock shaft 39 are 25 mounted the front and rear arms 42 and 43 by means of suitable collars 44 and 45 fitted to the shaft, each having a set screw for fastening the collar to the rock shaft.

The rear arm 43 is suitably formed and 30 extended to engage an arm 50 projecting upward from the shaft 34 carrying the shoe 37. The front arm 42 extends upward and has its upper end suitably formed to bear against a suitable abutment formed on the end of 35 the slide 51 which is operatively supported and guided by the head and shoulder of the screw 52. To the slide 51 is pivotally connected the arm 53 which is formed with the ear 54 to coöperate with means 55 which co- 40 operate with adjustable stops 56 on the carriage whereby lengthwise movement is transmitted to the slide 51 by the feeding movement of the carriage. Parts like the slide 51, arm 53, device 55 and margin stop 56, 45 have been in extensive use for a number of years in the Remington typewriters Nos. 10 and 11.

It will now be seen that when a predetermined line of print is completed the further feed movement of the carriage will actuate the interposing arm 35 whereby it will be moved into the path of the ear 36, and thereby directly block the escapement and indirectly block the key levers.

55 What I claim as new and desire to secure by Letters Patent is;

1. In a typewriting machine, the combination of a frame, a carriage movably mounted thereon, a carriage strap operatively connecting the carriage and the frame, tensioned to move the carriage for its writing movement and having its direction of movement reversed when the carriage is retracted, escapement mechanism including a movable 60 member the movement of which is necessary 65

for the operation of the escapement mechanism, an arm adapted to be moved into position to engage the said movable escapement member and prevent operation thereof or to be withdrawn therefrom, a movably mounted shoe frictionally engaging the carriage strap and moved thereby according to the direction of movement of the strap, and means operatively connecting said arm and said friction shoe whereby the arm is moved into locking engagement with the movable escapement member when the carriage is being retracted and the arm is disengaged when the carriage is making its writing movement. 70 75 80

2. In a typewriting machine, the combination of a frame, a carriage movably mounted thereon, a carriage strap operatively connecting the carriage and the frame, tensioned to move the carriage for its writing movement and having its direction of movement reversed when the carriage is retracted, escapement mechanism including a dog rocker the movement of which is necessary for the operation of the escapement mechanism, an arm adapted to be moved into position to engage the said dog rocker and prevent operation thereof or to be withdrawn therefrom, a movably mounted shoe frictionally engaging the carriage strap and moved thereby according to the direction of movement of the strap, and means operatively connecting said arm and said friction shoe whereby the arm is moved into locking engagement with the dog rocker when the carriage is being retracted and the arm is disengaged when the carriage is making its writing movement. 90 95 100 105

3. In a typewriting machine, the combination of a frame, a carriage movably mounted thereon, a carriage strap operatively connecting the carriage and the frame, tensioned to move the carriage for its writing movement and having its direction of movement reversed when the carriage is retracted, escapement mechanism including a dog rocker the movement of which is necessary for the operation of the escapement mechanism, an arm adapted to be moved into position to engage the said dog rocker and prevent operation thereof or to be withdrawn therefrom, a movably mounted shoe frictionally engaging the carriage strap and moved thereby according to the direction of movement of the strap, and a rock shaft supporting said arm and said friction shoe whereby the arm is moved into locking engagement with the dog rocker when the carriage is being retracted and the arm is disengaged when the carriage is making its writing movement. 110 115 120 125 130

4. In a typewriting machine, the combination of a frame, a carriage movably mounted thereon, means operatively connecting the carriage and the frame, a member mov-

ing in one direction when the carriage is making its feeding movement and moving in the other direction when the carriage is being retracted, escapement mechanism including a movable part the movement of which is necessary for the operation of the escapement mechanism, a locking member adapted to be moved into position to lock said movable part of the escapement mechanism or to be withdrawn therefrom, a movably mounted shoe frictionally engaging the said two-way-moving member and moved thereby and means operatively connecting said locking member and said friction shoe whereby the locking member is moved into locking position when the carriage is being retracted and is disengaged when the carriage is making its writing movement.

5. In a typewriting machine, the combination of a frame, a carriage movably mounted thereon, escapement mechanism for the carriage, a member moving in one direction when the carriage is making its feeding movement and moving in the other direction when the carriage is being retracted, a locking member adapted to be moved into position to lock said carriage escapement from movement, a movably mounted shoe frictionally engaging the said two-way-moving member and moved thereby and means operatively connecting said locking member and said friction shoe whereby the locking member is moved into locking position when the carriage is being retracted and is disengaged when the carriage is making its writing movement.

6. In a typewriting machine, the combination of a frame, a carriage movably mounted thereon, escapement mechanism including a movable member the movement of which is necessary for the operation of the escapement mechanism, an arm adapted to be moved into position to engage the said movable escapement member and prevent operation thereof and to be withdrawn therefrom, a finger movably mounted on the frame and adapted to be moved by the carriage when the carriage comes to the predetermined end of the line, means operatively connecting said finger and said arm whereby the arm is moved into locking engagement with the movable escapement member when the carriage moves said finger and a frictional connection between said arm and said movable carriage for withdrawing said arm from locking engagement.

7. In a typewriting machine, the combination of a frame, a carriage movably mounted thereon, a carriage strap operatively connecting the carriage and the frame, tensioned to move the carriage for its writing movement and having its direction of movement reversed when the carriage is retracted, escapement mechanism including a movable member the movement of which is necessary

for the operation of the escapement mechanism, an arm adapted to be moved into position to engage the said movable escapement member and prevent operation thereof or to be withdrawn therefrom, a movably mounted shoe frictionally engaging the carriage strap and moved thereby according to the direction of movement of the strap, means operatively connecting said arm and said friction shoe whereby the arm is moved into locking engagement with the movable escapement member when the carriage is being retracted and the arm is disengaged when the carriage is making its writing movement, a finger movably mounted on the frame and adapted to be moved by the carriage when the carriage comes to the predetermined end of the line, and means operatively connecting said finger and said arm whereby the arm is moved into locking engagement with the movable escapement member when the carriage moves said finger.

8. In a typewriting machine, the combination of a letter spacing escapement and frictionally actuated means for blocking and unblocking the escapement whereby printing is prevented during the retraction of the carriage and whereby printing is allowed during the feeding movement of the carriage.

9. In a typewriting machine, the combination of a letter spacing escapement, frictionally actuated means for blocking and unblocking the escapement, and means actuated by the feeding movement of the carriage for causing the said blocking means to function, whereby printing is prevented from the time of completion of said line of print until completion of the retractive movement of the carriage for the commencement of a new line of print.

10. In a typewriting machine, the combination of a carriage, a letter spacing escapement, frictionally actuated means for blocking the escapement, and line locking devices connected with said blocking means, the said blocking means being caused to function on the completion of a line of writing and maintained in blocking position during the retraction of the carriage.

11. In a typewriting machine, the combination with a carriage and a letter feed escapement, of a device coöperating with a member of said escapement to prevent a false operation thereof, and a frictional connection to render said device operative during the return motion of the carriage and non-operative during the advance of the carriage.

12. In a typewriting machine, the combination with a carriage and a letter feed escapement, of a lever having one arm adapted to coöperate with a member of said escapement to prevent a false operation thereof and having another arm frictionally actuated

whereby the first mentioned arm is held out of engagement with said escapement member during the advance of the carriage and held in engagement therewith during the retraction of the carriage.

13. In a typewriting machine, the combination of a carriage, a letter space escapement, and means for blocking a part of the escapement by a retractive movement of the carriage, said means being frictionally actuated.

14. In a typewriting machine, the combination of a carriage, a letter spacing escapement, and means for blocking a part of said escapement, said means being thrown into action during a retractive movement of the carriage and before the end of said movement.

15. In a typewriting machine, the combination of a carriage, a letter spacing escapement, a device for blocking a part of said escapement, and means for actuating said device extending to a part traveling forth and back with the carriage whereby said blocking device is moved into blocking position during a backward movement of said carriage.

16. In a typewriting machine, the combination with the printing means, the carriage and the letter feed escapement, of means including a frictionally actuated device for en-

gagement with said escapement to prevent a false step of the carriage between the ending of one line of writing and the printing of the character beginning the next succeeding line.

17. In a typewriting machine, the combination of a carriage, a letter spacing escapement, and means operative by a retractive movement of the carriage for preventing the escapement wheel from turning a false tooth-space at the beginning of a new line before the printing of the first letter thereof shall have been effected.

18. In a typewriting machine, the combination of a carriage, a letter spacing escapement, a device for engaging a part of said escapement, and means for maintaining said device out of action during the operation of writing and bringing said device into action during the return motion of the carriage.

19. In a typewriting machine, the combination of a carriage, an escapement mechanism, a blocking means therefor and means connected with the carriage for holding the blocking means inoperative during the forward letter spacing movement of the carriage.

In witness whereof I have affixed my signature this third day of November, 1919.

LOUIS P. DISS.
